UNITED STATES PATENT OFFICE.

HENRY A. HENDERSON, OF CONWAY, NEW HAMPSHIRE.

ELEVATOR.

SPECIFICATION forming part of Letters Patent No. 777,416, dated December 13, 1904.

Application filed December 19, 1903. Serial No. 185,843. (No model.)

To all whom it may concern:

Be it known that I, HENRY A. HENDERSON, a citizen of the United States, residing at Conway, in the county of Carroll and State of New Hampshire, have invented new and useful Improvements in Elevators, of which the following is a specification.

My invention relates to new and useful improvements in elevators, and more especially to means for operating the same; and its object is to provide mechanism of this character which will move the car of the elevator at a desired speed, but which will not permit the same to drop in the event of the breaking of the motor or of the parts connected thereto.

A further object is to employ an operating device the parts of which can be detached and replaced in the event of breakage.

With the above and other objects in view the invention consists in the novel construction and combination of parts, hereinafter more fully described and claimed, and illustrated in the accompanying drawings, showing the preferred form of my invention, and in which—

Figure 1 is a side elevation of my improved elevator-operating mechanism connected to a car-platform. Fig. 2 is a front elevation thereof. Fig. 3 is a bottom plan view of the arms and the rails connected thereto. Fig. 4 is a side elevation of a modified form of rail, and Fig. 5 is a vertical section through the modified form of rail and a portion of the platform mounted thereon.

Referring to the figures by numerals of reference, 1 is the platform of an elevator, and the same has guide-ears 2 at the sides thereof, which overlap guide-rails 3. Arranged upon the inner faces of these guide-rails are rollers 4, revolvably mounted upon horizontal pivot-pins 5. The rollers are spaced apart at regular intervals and for the purpose herein-after more fully described. A plate 6 is secured to the bottom of the platform 1 and has an extension 7, from which projects a stem 8, which forms a bearing for a gear 9. This gear meshes with a driving-gear 10, secured to one end of a shaft journaled in bearings 12 upon the bottom of platform 1 and adapted to be rotated in any suitable manner. De-

tachably secured to the lower surface of gear 9 by means of bolts 13 or in any other suitable manner are arms 14, arranged in series, and each series of arms is formed with or secured to a curved rail 15, having a strengthening-flange 16 at its inner edge. These curved rails 15 overlap at their ends and in plan view form a circle. The rails are spiral, and the distance between their overlapping ends is approximately equal to the diameters of the rollers 4. Any desired number of rails 15 may be used; but I preferably employ three, and each of these rails is slightly longer than one-third of the diameter of the circle formed by all of the rails. Any suitable means, such as a retaining-nut 17, may be employed for holding the arms 14 upon the stem 8.

The diameter of the circle formed by the rails 15 is substantially equal to the distance between the rails 3, and one of the rollers on each of the guide-rails is always contacted by one of the rails 15. When rotary motion is transmitted to gear 9 through gear 10 and shaft 11, the arms 14 and rails 15 will be rotated with the gear 9 and will be caused to successively engage the rollers upon the guide-rails. The rails 15 will move upward upon the rollers when rotating in one direction and will therefore cause the platform 1 to travel upward therewith. As one of the rails 15 leaves a roller 4 on one of the guide-rails the succeeding rail 15 will move into position upon the adjoining roller 4 upon said rail, and it will thus be seen that the car is at all times supported by the rails 15 and the rollers. By rotating the rails 15 in an opposite direction the platform can be caused to descend.

While I have shown two guide-rails 3, it will be understood that three or more may be employed. Moreover, instead of mounting the platform solely at the center thereof upon gear 9 the same may in addition be provided with rollers 18, journaled in brackets 19, secured to the platform, and these rollers contact with a circular track 20, secured to the inclined rails. I have shown this modified construction in Figs. 4 and 5. By mounting the platform in this manner there is no dan-

ger of the platform tilting or becoming displaced, and the friction caused by the operation of the hoisting mechanism is reduced to the minimum. It will be seen that as the 5 arms 14 are detachable any one of the hoisting-rails 15 can be readily removed and replaced in case of breakage. Moreover, owing to the pitch of the rails 15 the platform is prevented from falling in the event of the 10 breakage of the operating-motor or any of the parts connected thereto. It will be seen that the flanges 16 strengthen the rails 15 longitudinally and also serve to limit the lateral movement of the rails in relation to the 15 rollers 4.

In the foregoing description I have shown the preferred form of my invention; but I do not limit myself thereto, as I am aware that modifications may be made therein without departing from the spirit or sacrificing any 20 of the advantages thereof, and I therefore reserve the right to make such changes as fairly fall within the scope of my invention.

Having thus described the invention, what 25 is claimed as new is—

1. The combination with guide-rails having rollers journaled thereon; of a platform, a stem secured to and projecting from the platform, a gear revolvably mounted thereon, arms secured to and independently removable from 30 the gear, inclined curved hoisting-rails upon

the arms and having overlapping ends spaced apart, said rails being adapted to successively ride upon the rollers.

2. In mechanism of the character described, 35 the combination with guide-rails having rollers journaled thereon; of a platform, similar independently-removable, inclined hoisting-rails connected to the platform, means for rotating the rails to cause them to successively 40 ride upon the rollers, a circular track formed of sections connected to the rails, and means extending from the platform whereby said platform is supported by the track.

3. The combination with guide-rails having 45 rollers journaled thereon; of a platform, a stem secured to and projecting from the platform, a gear revolvably mounted thereon, arms secured to and independently removable from the gear, inclined curved hoisting- 50 rails upon the arms and having overlapping ends spaced apart, said rails being adapted to successively ride upon the rollers, a circular track formed of sections secured to the inclined rails, and rollers secured to the platform and contacting with the track.

In testimony whereof I affix my signature in presence of two witnesses.

HENRY A. HENDERSON.
